CLAIM

The ornamental design for a cart, as shown and described.

DESCRIPTION

FIG. 1 is a front perspective view of my new design for a cart; FIG. 2 is a side elevation view of the right and left sides, which are mirror images, of FIG. 1;

FIG. 3 is back side elevation view of FIG. 1;

FIG. 4 is a front side elevation view of FIG. 1;

FIG. 5 is a top plan view of FIG. 1;

FIG. 6 is a bottom plan view of FIG. 1;

FIG. 7 is a front perspective view of a second embodiment for a cart;

FIG. 8 is a side elevation view of the right and left sides, which are mirror images, of FIG. 7;

FIG. 9 is back side elevation view of FIG. 7;

FIG. 10 is a front side elevation view of FIG. 7;

FIG. 11 is a top plan view of FIG. 7; and,

FIG. 12 is a bottom plan view of FIG. 7.

The broken line showing of wheels and back basket in FIGS. 7 through 12 is included for the purpose of illustrating environment and forms no part of the claimed design.
